UNITED STATES PATENT OFFICE.

SAMUEL D. NICHOLS, OF FOND DU LAC, WISCONSIN.

RIBBED ARTICLE AND PROCESS OF FORMING SAME.

Application filed February 16, 1923. Serial No. 619,535.

To all whom it may concern:

Be it known that I, SAMUEL D. NICHOLS, a citizen of the United States, residing at Fond du Lac, in the county of Fond du Lac 5 and State of Wisconsin, have invented certain new and useful Improvements in Ribbed Articles and Processes of Forming the Same; and I do declare the following to be a full, clear, and exact description of the 10 invention, such as will enable others skilled in the art to which it appertains to make and use the same.

My invention relates to improvements in articles of manufacture embodying a sheet 15 of leather or other flexible material having a rib on its obverse side, the present disclosure being directed to a shoe vamp.

One object of the invention is to provide a ribbed article in which the rib will be uniform throughout its length, instead of being 20 irregular at portions, as now results from the present day methods of forming the rib.

A further object is to provide an improved process for forming the rib, consisting in 25 passing two spaced parallel rows of stitching through the sheet of material and drawing the two rows of stitching toward each other at the reverse side of the sheet, causing protrusion of the material at the ob- 30 verse side of said sheet to form a rib between the two rows of stitching.

With the foregoing in view, the invention resides in the novel subject matter hereinafter described and claimed, the description 35 being supplemented by the accompanying drawing.

Figure 1 is a plan view of a shoe vamp formed with a rib in accordance with my invention.

40 Figure 2 is a lower side elevation on an enlarged scale showing the preferred manner of drawing the two rows of stitching together and holding them.

Figure 3 is an enlarged transverse sec- 45 tional view as indicated by line 3—3 of Fig. 1.

In carrying out my invention, I take the sheet of material to be ribbed, such as a 50 shoe vamp indicated by the reference numeral 1 in the drawing and form two paral-

lel, spaced rows of stitching 2 therethrough at the proper locations. Machine stitching is preferably used and the two rows may well be formed by a double needle machine in order to insure that they shall be spaced 55 equidistantly throughout their length. However, it will be understood that each row could be formed separately, either by a machine operation or by hand.

After forming the rows of stitching 2, 60 these rows are drawn toward each other and held at the reverse side of the sheet 1 and while other means could be employed for performing this operation, I prefer to lace a suitable leash 3 through the stitching 65 of the rows, using this leash to draw the rows tightly together. This operation causes protrusion of the material between the two rows of stitching at the obverse side of the sheet 1 and thus forms the desired rib which 70 will be uniform throughout its length. This uniformity cannot be obtained by the methods now commonly used and furthermore, the latter require a great deal of 75 trouble and time.

Excellent results have been obtained from the details of construction and the method steps herein disclosed and they are therefore preferably followed. I wish it understood however that within the scope 80 of the invention as claimed, numerous minor changes may be made. Furthermore, the use of my invention is not restricted to any particular field, but may be employed wherever it is desired to form a rib on a 85 piece of flexible sheet material.

I claim:

1. The process of forming a rib on sheet material, consisting in forming two spaced parallel disconnected rows of stitching 90 through uniform thicknesses of the same sheet of material, and by an entirely separate operation passing a lace through adjacent stitches of said rows and by said lace drawing said rows into contact with each 95 other at one side of the sheet to bulge the material at the other side of said sheet and form the rib.

2. The process of forming a rib on sheet material, consisting in simultaneously 100

forming two disconnected parallel rows of rows and by said lace drawing said rows into contact with each other at one side of the sheet to bulge the material at the other side of said sheet and form the rib.

5 which the stitching operation is performed, and by an entirely separate operation passing a lace through adjacent stitches of said

In testimony whereof I have hereunto affixed my signature.

SAMUEL D. NICHOLS.
